UNITED STATES PATENT OFFICE

GILBERT C. WATERS, JR., OF ROCHESTER, NEW YORK, ASSIGNOR TO H. F. MORRIS CORPORATION, OF ROCHESTER, NEW YORK, A CORPORATION OF NEW YORK

DESIGN FOR A CARD TABLE COVER

Application filed June 29, 1932. Serial No. 44,217. Term of patent 7 years.

To all whom it may concern:

Be it known that I, GILBERT C. WATERS, JR., a citizen of the United States, residing at Rochester, in the county of Monroe and State of New York, have invented a new, original, and ornamental Design for a Card Table Cover, of which the following is a specification, reference being had to the accompanying drawing, forming part thereof.

In the drawing:

The figure is a plan view of a card table cover showing my new design.

I claim:

The ornamental design for a card table cover substantially as shown.
